UNITED STATES PATENT OFFICE.

RICHARD LIEBAU, OF BERKLEY HEIGHTS, NEW JERSEY, ASSIGNOR TO RUTH WYLLYS CHAPTER, DAUGHTERS OF THE AMERICAN REVOLUTION, OF HARTFORD, CONNECTICUT, AN ASSOCIATION.

DESIGN FOR AN EMBLEM.

52,663.

Specification for Design.

Patented Nov. 12, 1918.

Application filed May 24, 1918. Serial No. 236,435. Term of patent 3½ years.

To all whom it may concern:

Be it known that I, RICHARD LIEBAU, a citizen of the United States, residing at Berkley Heights, in the county of Union and State of New Jersey, have invented a new, original, and ornamental Design for an Emblem, of which the following is a specification, reference being had to the accompanying drawing, forming a part thereof.

The figure shows a plan of an emblem bearing my new design.

I claim:

The ornamental design for an emblem as shown.

RICHARD LIEBAU.
